UNITED STATES PATENT OFFICE

2,420,990

PORTABLE EXCAVATOR

Fred L. White, Marion, Ohio, assignor to The
Osgood Company, Marion, Ohio, a corporation
of Ohio

Application June 11, 1945, Serial No. 598,804

6 Claims. (Cl. 214—135)

1

This invention relates to portable excavators and in its more specific aspects is directed to an improved dipper operating mechanism.

One of the objects of the invention is to provide a dipper manipulating mechanism that is entirely cable controlled or operated which has the dipper under complete control regardless of where the working face happens to be.

Another object of the invention is to provide a cable manipulated dipper that is as completely subject to control when the excavator is close by or is removed some distance from the working face.

Another object of the invention is to provide a cable operated dipper manipulator that will allow the dipper handle to be extended to its maximum extent whether the boom is in its lowest or most elevated position.

A still further object of the invention is to provide a means whereby two forces may be applied to substantially opposite ends of the handle without balancing the forces therein for manipulating the dipper and its handle.

Other and further objects of the invention will occur to those skilled in the arts to which this invention pertains as the description proceeds which taken in connection with the accompanying drawings sets forth a preferred embodiment of the invention but such disclosure is not to be construed as a limitation of the invention which is limited only by the appended claims and any and all modifications, alterations and variations of structure coming within the spirit and scope thereof are deemed to be included herein.

In the drawings:

Fig. 1 shows a perspective view of a portion of an excavator incorporating the invention.

Fig. 2 shows a view of a double winding drum and controls therefor.

The reduction of weight on the boom and dipper construction for portable excavators without a reduction in the mechanical strength is an essential in the art. Prior art constructions have employed heavy, cumbersome shipper shaft drives with complicated mechanism to reversely control its operation. This invention is directed to a mechanism for reducing the number of parts in the shipper drive without decreasing the maneuverability of the dipper and its handle and with an increase in the rapidity of control.

The objects and advantages set forth above are obtained in a structure set forth in the accompanying drawings in which 1 is a portion of the traction and chassis elements of a portable excavator. An upper body 2 is shown rotatably

2

mounted thereon in the usual manner common to the art.

5 A boom 3 is pivotally mounted on the upper body 2 by means of a pin and bracket mechanism (not shown). The vertical position or the angle of the boom with the horizontal is controlled by cables 4, 4 operatively associated with the upper end of the boom 3 and are wound and unwound on an appropriate winch (not shown) mounted on the upper body 2.

10 The boom 3 has a fixture thereon functioning as a dipper handle receiving element or saddle block 5 mounted on a pivot 6 secured to the boom 3. A dipper 7 is fixed to the end of a handle 8, 15 with said handle 8 slidably received in the saddle block 5. The handle 8 extends through an appropriate slot 9 in the boom 3 to thereby enable the dipper assembly to move relatively to the boom 3.

20 Rotatably mounted in suitable journals arranged on the upper body 2 is a double winch or winding drum mechanism 10 set forth in more particular detail in Fig. 2. This mechanism has two drums 11 and 12 supported on a shaft 13. 25 Power is supplied to the shaft by means of a gear 14 which is driven from a suitable power source mounted on the upper body 2. Wheel 15 is likewise mounted on the shaft 13 with the drums 11 and 12 between it and gear 14. Associated with gear 14 is a clutch 16 and associated with the wheel 15 is a clutch 17. Brake mechanisms 18 and 19 are associated with the drums 11 and 12 respectively. The foregoing double drum construction is well known to the art and both drums are jointly or severally operable by means of suitable controls manually actuated.

35 The dipper 7 is retracted and hoisted by means of a cable 20 secured to and windable on the drum 11. It is then led over a sheave 21 rotatably mounted on the end of boom 3 and is then led through padlock pulley or sheave 22, thence over sheave 23 also rotatably mounted on the end of boom 3 and is then led around sheave 24 rotatably mounted on the bearing or saddle block 5 40 for the dipper handle 8. The end of cable 20 is anchored to the dipper handle 8 near the dipper 7. When cable 20 is being wound on the drum 11 it will hoist and retract the dipper 7. Gravitational action will lower the dipper 7 whenever 45 the clutch 16 and brake 19 are both disengaged. Brake 19 is used to hold and regulate the downward movement of the dipper 7.

50 A cable 26 is secured to and windable on the drum 12 which drum acts as a crowd control for the dipper 7. The cable is then led around

sheave 27 rotatably mounted on the lower part of the slide bearing or saddle block 5 and is then led around sheave 28 rotatably mounted on the end of dipper handle 8 and the cable 26 and then may be suitably anchored to the saddle block 5. Cable 26 when wound on the drum 12 will crowd the dipper 7 into the working face of the material being excavated. Gravitational action and the retract cable 20 will bring the shovel or dipper 7 back to its normal position, and brakes 18 and 19 can hold the dipper 7 in any desired position.

Each of the cables 20 and 26 and their respective winding drums 11 and 12 may be independently or jointly operated by control clutches 16, 17 and brakes 18, 19. Retracting of the dipper, especially when it has been raised to a high position is largely a gravity action but when it is in a lowered position it is retracted by the cable 20 and also when the boom 3 is in a lowered position. The full output of the engine or prime mover delivered to the gear 14 is applied to the dipper 7 and its handle 8. The independent crowd enables the operator to shake the dipper to release adhering materials. When the clutch and brake controls 16, 17 and 18, 19 for the drums 11 and 12 respectively are properly jointly and severally actuated a rapid and accurate control of the dipper is achieved whatever the elevation of the boom 3 or the degree of extension of the handle 8 through the boom 3 in the saddle block 5.

That which is regarded new, novel and useful and which is sought to be protected by Letters Patent of the United States is as follows:

1. An excavator comprising an upper body; a boom on said upper body; a pivoted saddle block on said boom; a dipper; a handle for said dipper received in said saddle block; a pair of winding drums on said upper body; a cable anchored near one end of said handle connected to one of said winding drums and operatively associated with said dipper to hoist and retract said dipper; a cable connected to the other winding drum and to the other end of the handle to crowd said dipper; and clutch and brake means associated with said drum to selectively control the operation of each winding drum.

2. An excavator comprising an upper body; a boom on said upper body; a dipper; a handle on said dipper; means on said boom receiving said handle to pivot said handle relative to said boom; a pair of winding drums on said upper body; a cable connected between one end of said handle and one of said drums operatively associated with said dipper to hoist and retract said dipper, said cable applying axial movement to said handle through said handle receiving means; a cable operatively connected to the other end of said handle and to the other winding drum to crowd said dipper, said cable axially moving said handle in said handle receiving means; and a clutch and a brake associated with each drum to selectively control the retracting and hoisting and the crowding of said dipper.

3. An excavator comprising an upper body; a boom on said upper body; a dipper; a handle on said dipper; a saddle block on said boom in which said handle is slideable; a double drum winch on said upper body, each drum being individually operative; a first sheave on said saddle block; a cable anchored near one end of said handle passed about said first sheave then operatively associated with sheaves on said boom and dipper connected to one of said drums to hoist and retract said dipper upon rotation of said drum; a second sheave on said saddle block; and a cable

secured to the other drum passed around said second sheave and anchored such that upon actuation of said drum said dipper will be crowded.

4. An excavator comprising an upper body; a boom on said upper body; a saddle block pivotally mounted on said boom; a handle in said saddle block; a dipper secured to said handle; a double drum winch on said upper body; two sheaves rotatably mounted on said saddle block, one on each side thereof; a cable secured to one of drums passing around one of said sheaves and anchored such that the operation of said drum will move said handle in said saddle block to crowd said dipper; sheaves associated with said boom and with said dipper; a cable anchored on said handle near said dipper passing around said other of said sheaves on said saddle block, and thence about said sheaves on said boom and said dipper secured to and windable on the other of said drums which upon rotation will hoist and retract said dipper; and means to selectively control said drums such that said dipper will be selectively hoisted, retracted or crowded.

5. In a portable excavator; an upper body; a boom on said upper body; sheaves rotatably mounted on said boom; a dipper having a sheave thereon; a handle for said dipper; a saddle block pivotally mounted on said boom in which said handle is slideably mounted; a pair of winding drums on said upper body; sheaves rotatably mounted on said saddle block, one on each of two sides thereof; a cable anchored on said handle, passing around one of said saddle block sheaves, then about said boom and dipper sheaves and secured to one of said winding drums to hoist and retract said dipper; a cable secured to the other winding drum, thence about the other saddle block sheave and anchored with respect to said handle to enable it to axially move said handle in said saddle block to crowd said dipper; and means to control said drums to thereby hoist, retract or crowd said dipper.

6. In a portable excavator; an upper body; a boom mounted on said upper body; a saddle block pivoted to said boom; a dipper; a handle for said dipper slideable in said saddle block; sheaves on said boom and dipper; a sheave mounted on each of two sides of said saddle block; a pair of winding drums on said upper body; a cable anchored near one end of said handle, trained about one of said saddle block sheaves, then about said boom and dipper sheaves and connected to one of said winding drums to hoist and retract said dipper; another cable connected to the other winding drum, passed about the other sheave on said saddle block and anchored to enable it to move said handle in said saddle block to crowd said dipper; and means to selectively actuate said winding drums to thereby hoist, retract or crowd said dipper.
